UNITED STATES PATENT OFFICE

2,610,393

HAIRCUTTING AND COLLECTING DEVICE

Philo L. Hammond, Massillon, Ohio

Application May 28, 1951, Serial No. 228,631

4 Claims.

(Cl. 30—30)

1

This invention relates to new and useful improvements in hair cutting devices and the primary object of the present invention is to provide a small and compact rigid receptacle having an open side for receiving cut hair together with cutting means, mounted in the receptacle along a toothed edge at the open side of the receptacle, for cutting hair as the device is manipulated through a user's hair by one hand of a user.

Another important object of the present invention is to provide a hair cutting and collecting device including novel and improved means for detachably securing a pair of relatively inclined razor blades within the same.

A further object of the present invention is to provide a hair cutting and collecting device of the aforementioned character wherein the receptacle is formed of two detachably connected plastic walls that are quickly and readily separated to permit cleaning thereof and removal of the hair passing into the receptacle.

A still further aim of the present invention is to provide a hair trimming and collecting device that is simple and practical in construction, strong and reliable in use, neat and attractive in appearance, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present invention showing one of the holding screws removed from its normal position to permit separation of the receptacle forming halves;

Figure 2 is a longitudinal sectional view taken substantially on the plane of section line 2—2 of Figure 1; and,

Figure 3 is a transverse vertical sectional view taken substantially on the plane of section line 3—3 of Figure 2.

Referring now to the drawings in detail, wherein for the purpose of illustration, there is disclosed a preferred embodiment of the present invention, the numeral 10 represents an elongated housing member or hair collecting receptacle that is composed of two, preferably plastic, concavo-convexed walls 12 and 14.

A flange 16 is provided on the rear edge and end edges of the wall 12 and fits behind the end edges and rear edge of the wall 14. Rigid webs 18 project outwardly from the ends of the walls 12

and 14, and the webs 18 are integrally formed with enlargements 20. The webs and enlargements of the wall 12 rest against the webs and enlargements of the wall 14, and the enlargements on the wall 12 are formed with apertures that register with internally threaded apertures in the enlargements on the wall 14, so that screws 22 may be employed for detachably securing the enlargements of one wall to the enlargements of the other wall, whereby the walls may be separated for removing hair collected therebetween and for cleaning.

The forward side of the receptacle 10 is formed with an entrance opening for cut hair, or stated differently, the forward edge 24 of the wall 12 is spaced sufficiently from the forward edge 26 of the wall 14 to define an entrance opening 0 for cut hair. The forward edge 26 of the wall 14 is formed with a plurality of transverse inwardly tapering slots to form comb teeth 28 between adjacent slots and a toothed edge for the wall 14.

A pair of relatively inclined razor blades 30 and 32 are held clamped against the inner face of the wall 14 by an elongated clamping plate 34 whose ends are secured to the wall 14 by headed fasteners 36 whose shanks extend through the wall 14 and the ends of the plate 34. The threaded inner ends of the fasteners 36 receivably engage nuts 38 that are tightened to hold the plate 34 against the inner face of wall 14.

Plate 34 is formed with a concavo-convexed portion 40 that overlies the reinforced edges 42 of the blades 30, 32 and whose forward edge bears against the blades 30, 32 to hold the blades against the inner face of wall 14.

The inner faces of the teeth 28, at their inner ends, are formed with notches 44 that form seats for the beveled edges of the blades 30 and 32. The notches 44 in one half of the teeth 28 lie in a plane inclined relative to the plane through the notches 44 in the other half of the teeth, so that the blades 30, 32 will be relatively inclined as shown in Figure 2.

In practical use of the present invention, the receptacle 10 is grasped by one hand of a user and passed through the user's hair with the toothed edge of wall 14 functioning as a comb to lift the hair and the blades 30, 32 will cut the hair whereupon the cut hair will enter the receptacle 10.

Having described the invention, what is claimed as new is:

1. A hair cutting device comprising a housing member composed of two concavo-convexed walls secured together, said housing member

having an opening in one side, one of said walls having a toothed comb forming edge at the open side of the housing member, and cutting means mounted on said one wall and disposed in said housing member, said cutting means overlying the toothed edge of said one wall, said toothed edge including a plurality of teeth having inner faces formed with notches, and said cutting means including a pair of relatively inclined razor blades having cutting edges seated in said notches.

2. A hair cutting device comprising a housing member forming a hair collecting receptacle, said housing member being composed of upper and lower detachably connected concavo-convex walls, said housing members having an opening at one side to receive cut hair, said lower wall including a toothed edge at the opening in said housing member, cutting means overlying the lower wall and the toothed edge of said lower wall, an elongated clamping plate having a portion overlying the cutting means and holding the cutting means against said lower wall, and fasteners extending through said lower wall and said plate and securing the plate to the lower wall.

3. A hair cutting and collecting device comprising a receptacle sufficiently small to be grasped and manipulated by one hand of a user, said receptacle including first and second elongated concavo-convex walls, said walls each including end edges and forward and rear edges, a flange about the end edges and rear edge of the first wall seated behind the end edges and rear edge of the second wall, means on the ends of said walls detachably securing the walls together to form the receptacle, the forward edges of said walls being spaced apart to define an entrance opening for hair to enter the receptacle, the forward edge of said second wall being toothed to form a comb, and a pair of blades held on the inner face of said second wall and including beveled edges overlying the teeth of said toothed edge, the teeth of said toothed edge including inner faces each having a notch, the beveled edges of said blades being disposed in said notches.

tacle, the forward edge of said second wall being toothed to form a comb, and a pair of blades held on the inner face of said second wall and including beveled edges overlying the teeth of said toothed edge.

4. A hair cutting and collecting device comprising a receptacle sufficiently small to be grasped and manipulated by one hand of a user, said receptacle including first and second elongated concavo-convex walls, said walls each including end edges and forward and rear edges, a flange about the end edges and rear edge of the first wall seated behind the end edges and rear edge of the second wall, means on the ends of said walls detachably securing the walls together to form the receptacle, the forward edges of said walls being spaced apart to define an entrance opening for hair to enter the receptacle, the forward edge of said second wall being toothed to form a comb, and a pair of blades held on the inner face of said second wall and including beveled edges overlying the teeth of said toothed edge, the teeth of said toothed edge including inner faces each having a notch, the beveled edges of said blades being disposed in said notches.
